SYLVANIA, A CORPORATION OF NEW JERSEY.

DRAIN CONNECTION.

No. 931,019

Specification of Letters Patent. Patented Aug. 10, 1909.

Application filed January 20, 1909. Serial No. 473,353.

To all whom it may concern:

Be it known that we, EDWARD L. DAWES, of New Brighton, Beaver county, Pennsylvania, and JOHN C. REED, of Pittsburg, 5 North Side, Allegheny county, Pennsylvania, both citizens of the United States, have invented a certain new and useful Drain Connection, of which the following is a specification.

10 Our invention relates to drain connections for sinks, tubs, basins and the like.

Throughout this specification for the sake of brevity we will describe the invention as used in connection with a sink, but it is to 15 be understood that the invention is applicable equally well to tubs or any other tub-like vessels.

Our invention is designed to be used principally in connection with high-grade sinks 20 or tubs, the inner surfaces of which are covered with vitreous enamel. Because of the character of the drain connections which have heretofore been used on enameled sinks, it has been considered necessary to provide a 25 recess in the sink bottom surrounding the drain opening. It is exceedingly difficult to properly enamel metal surfaces having abrupt angles such as are found in sinks provided with such a recess, and the enamel ad- 30 jacent to the opening is frequently cracked or crazed for reasons understood by those skilled in this art. Our invention avoids these disadvantages by providing an enameled sink with a straight walled drain opening, the upper edge of which immediately 35 adjoins the inner bottom surface of the sink without any intervening recess. The said surface may be made entirely free from sharp angles or abrupt changes in direction.

40 In carrying out our invention in a preferred form the parts of the connection originally separate from the sinks are so constructed and arranged that when in position certain portions of the fitting protrude 45 above the normal inner bottom surface of the sink or tub. When the sink has the ordinary approximately flat bottom, this protruding portion of the connection causes 50 pots or other utensils placed in the sinks or tub over the drain opening to tilt or joggle and the free movement of utensils along the bottom surface may be impeded by the up- 55 standing part of the fitting. To avoid these disadvantages and also facilitate the drain-

ing of the fluid contents from the sink the 55 sink bottom is provided with a gradual depression surrounding the drain opening, this depression being of such depth that when the drain connection is put in position the highest portion of the connection within 60 the sink is approximately level with the main inner bottom surface of the sink. By this arrangement any utensils placed in the sink will stand perfectly level whether placed over or near the drain opening or not. 65

Another object accomplished by the invention is the construction and arrangement of the parts of the connection so that although, as has been stated, a portion of the connection protrudes above the inner bottom surface of the sink, the entire fluid contents of the sink may pass out through the drain opening without impedance by any part of the fitting. 70

The use of our invention avoids any tendency to chip or craze the enamel surrounding the drain opening and at the same time the appearance of such portions of the connection as may be seen from within the sink is very ornamental and attractive. 75

In the accompanying drawing we show an exemplifying structure embodying the invention, but it is to be understood that the invention is capable of embodiment in different forms. 80

Figure 1 is a vertical section through a portion of a sink and drain connection. Fig. 2 is an elevation of the connection, the sink bottom being shown in section on the center line of the drain opening. Fig. 3 is 90 a top view of the nipple removed from the other parts of the appliance. Fig. 4 is a top view of the strainer by itself. 95

Reference character 1 designates the sink or the like. The principal part of the bottom of the sink is approximately flat and horizontal as usual. The drain opening 2 passes through the sink bottom in any convenient place, usually near one end. The opening is usually circular and has a perfectly straight cylindrical wall passing through the bottom of the sink. 100

3 is a depression in the sink bottom surrounding the drain opening and joining the normal surface of the sink with a gradual 105 curvature.

Sinks or tubs of the class with which this invention is generally employed are usually

covered on their inner surface with vitreous enamel but the invention is also applicable to vessels which are not so enameled and for this reason and for the sake of clearness it is not attempted to show the enamel in the drawing. It is to be noted especially that the inner bottom surface of the sink extends directly to the drain opening which it joins without any intervening recess and without any abrupt changes of direction, or angles. It is possible for this reason to perfectly enamel the sink bottom directly up to the drain opening, thereby preventing the loss occasioned by irregular shapes or recesses either in manufacture or after the article has been in use.

A nipple 5 provided with radially extending fingers 6 is passed through the drain opening so that the cylindrical portion of the nipple 7 extends below the bottom portion of the sink. The fingers then rest upon the inner bottom surface of the sink adjacent to the opening. It will be apparent that the separated fingers thus form in effect a radiating flange provided with one or more openings through which residual fluid may drain from the sink. The tubular portion 7 is exteriorly threaded and a nut 8 engaging the thread compresses a gasket 9 against the bottom of the sink forming a water seal. The tubular portion of the nipple is discontinued considerably below the inner bottom surface of the sink and the fingers 6 are widely separated as may be seen in Fig. 3 so that the nipple itself offers no perceptible resistance to the flow of water even at its lowest level through the drain opening. The nipple 5 has a cross-bar 10.

The strainer 11 is of inverted dish shape and preferably has a substantially flat top. The substantially vertical side 12 of the strainer is just deep enough to touch the inner bottom surface of the sink and enable the top of the strainer to rest on the tops of the finger 6. At the center the strainer is depressed in making it, or countersunk to receive a screw head and a screw 13 passes through the strainer at this point and engages a threaded opening 20 formed in cross-bar 10. The screw-head rests in the counter-sink flush with the upper surface of the strainer. The strainer has top openings 14 through which the bulk of the water passes, and side openings 15 which extend to the inner bottom surface of the sink and permit the escape of water after its level is lower than the top of the strainer. Without these side openings in this kind of a drain connection some of the fluid would be trapped in the tub by the strainer. The fingers 6 and the bottom of the side wall of the strainer rest on the bottom of the depression 3 adjacent to the drain opening and the depth of the depression is so calculated that, as shown in Fig. 1, the top of the strainer is

approximately level with the main inner bottom surface of the sink. By this arrangement any utensils placed in the sink over or near the drain opening may rest perfectly level, the same as if no part of the connection projected within the sink.

The drain pipe 16 may be connected to the nipple in any convenient way but in a preferred construction the pipe is provided with a flange 17 which rests against the end of the 75 nipple and a nut 18 engaging the screw thread on the nipple has a flange 19 inwardly extending and engaging flange 17 and serving to urge the latter tightly against the end of the nipple.

We claim:

1. The combination of an enameled sink provided with a drain opening surrounded by a gradually sloping depression, a drain pipe and a connection intermediate the drain pipe and the sink at the drain opening, a portion of the connection extending within the sink above the bottom of said depression.

2. The combination of an enameled sink provided with a drain opening surrounded by a gradual depression, a drain pipe and a connection intermediate the drain pipe and the sink at the drain opening, a portion of the connection extending within the sink above the bottom of said depression, so that the highest portion of the connection is substantially level with the main inner bottom surface of the sink.

3. The combination of a sink, provided with a drain opening and a depression surrounding the opening, a nipple passing through the opening and having members engaging the inner bottom surface of the sink adjacent to the opening, a water seal intermediate the nipple and the sink bottom and a strainer secured to the nipple, the top of the strainer being substantially level with the principal portion of the inner sink bottom.

4. The combination of a sink, the bottom of which is provided with a circular drain opening and a shallow depression surrounding the opening, a nipple passing through the opening and provided with fingers resting on the bottom of the depression adjacent to the opening, a nut engaging a screw thread on the nipple below the sink bottom, a water seal intermediate the nut and the outer bottom surface of the sink, a strainer inclosing the drain opening and the fingers 115 on the nipple, the strainer being provided with top perforations and side perforations adjoining the inner surface of said depression and means for securing the strainer to the nipple.

5. The combination of a sink, the bottom of which is provided with a circular drain opening and a shallow gradual depression surrounding the opening, a nipple passing through the opening and provided with fin-

gers engaging the inner surface of the depression adjacent to the opening, a nut screw threaded on the nipple below the sink bottom, a gasket between the nut and the sink bottom, a strainer within the sink inclosing the said fingers and the drain opening, said strainer having top perforations and side perforations adjoining the bottom of the depression, the upper surface of the strainer 10 being approximately level with the principal portion of the inner sink bottom.

6. The combination of an enameled sink or the like having a substantially flat horizontal bottom provided with a straight drain 15 opening, a shallow gradual depression surrounding the drain opening and joining the opening without any intervening recess, a nipple passing through the opening and hav-

ing a flange resting on the inner surface of the sink adjacent to the opening, the flange 20 being provided with a passage for drainage of residual fluid and a strainer overlying the nipple and provided with top openings and side openings adjoining the inner bottom surface of the depression, the top of the 25 strainer being substantially level with the main inner bottom surface of the sink.
